HAND STRAP TENSIONING TOOL

Bernard T. McFerren, Youngstown, and Fred S. Seybert, Warren, Ohio, assignors, by mesne assignments, to Sharon Steel Corporation, Sharon, Pa., a corporation of Pennsylvania

Application June 14, 1951, Serial No. 231,588

6 Claims. (Cl. 254—51)

1

The invention relates generally to tools for stretching or tensioning metal straps or bands around a bundle or package, the overlapped ends of the straps being then secured together by a suitable sealing tool. More particularly, the invention relates to an improved hand stretching tool having novel means for raising the feed wheel to permit insertion of the overlapped ends of the strap between the feed wheel which engages the top end and the anchoring plug which engages the bottom end.

It is customary while holding the tool with the feed wheel adjusted or raised, to apply the tool laterally over the overlapped ends of the strap to position the strap ends directly under the feed wheel, whereupon the feed wheel is lowered to engage the top end of the strap.

In certain prior hand stretching tools such as that shown in U. S. Patent No. 1,969,115, issued August 7, 1934, to A. T. Bergstrom, the feed wheel is mounted on an eccentric shaft which is rotatably adjustable by a separate handle for raising and lowering the feed wheel. This adjusting handle projects laterally from one side of the tool and causes the tool to be unbalanced. Moreover, the operation of the laterally projecting adjusting handle requires either the use of both hands or holding the tool in one hand and operating the handle by pushing it against a solid object like the edge of a table, and this places the tool in an awkward position.

Furthermore, in such prior tools, if the feed wheel and eccentric shaft are not machined to fit substantially perfectly, when the tensioning handle is oscillated during the stretching operation the feed wheel tends to slip on the metal strapping, with the result that the operator has to hold down on the adjusting handle while oscillating the tensioning handle.

It is an object of the present invention to provide a novel hand tensioning tool in which the feed wheel is adjusted by manipulation of the tensioning handle and does not require a separate adjusting handle.

Another object is to provide a novel hand tensioning tool in which the feed wheel is raised and held in raised position using one hand only which at the same time supports the tool in position to apply it to the overlapped ends of the band.

More specifically, it is an object of the present invention to provide a novel hand tensioning tool in which the feed wheel is raised by squeezing the tensioning handle.

A further object is to provide a novel hand tensioning tool in which the feed wheel is easily adjusted but does not slip on the strap during the tensioning operation.

A still further object is to provide a novel hand tensioning tool which is lighter in weight, better balanced and more easily manipulated than prior tensioning tools.

These and other objects are accomplished by

the parts, improvements, combinations and arrangements comprising the present invention, a preferred embodiment of which is shown in the accompanying drawings and described in the specification as exemplifying the best known mode of carrying out the invention, the nature of the invention being set forth in the following general statement, and the scope of the invention being defined in the appended claims.

10 In general terms, the novel tool includes a feed wheel journaled on a shaft which is pivotally mounted for swinging upwardly in slots in a frame to raise the feed wheel with respect to the frame, the tensioning handle being journaled on the feed wheel shaft and having a ratchet pawl for driving the feed wheel, there being a shoulder on the frame on which to rock the tensioning handle and raise the feed wheel by releasing the pawl and squeezing the handle toward the frame, and there being a stop on the handle operatively connected to the pawl and normally engaging the frame to prevent rocking the handle to raise the feed wheel.

20 Referring to the drawings forming part hereof, in which a preferred embodiment of the invention is shown by way of example;

Figure 1 is a plan view of the improved tool, part of the handle being broken away;

Fig. 2 is a side elevation thereof, parts being broken away;

Fig. 3 is a front end view thereof with parts broken away;

Fig. 4 is a fragmentary longitudinal sectional view as on line 4—4, Fig. 1;

35 Fig. 5 is a side elevation with parts broken away and in section, showing the manner of releasing the pawl and squeezing the handle lever to raise the feed wheel;

Fig. 6 is a fragmentary longitudinal sectional view as on line 6—6, Fig. 1; and

40 Fig. 7 is a transverse sectional view as on line 7—7, Fig. 4.

Similar numerals refer to similar parts throughout the several views of the drawings.

45 The improved tool preferably includes a main frame indicated generally at 10 which is provided with spaced bases or feet 11 and 12 adapted to rest upon a surface of a bundle or package around which the metal strap or band is being tensioned or stretched. The overlapping ends b and b' of the band are adapted to be positioned over the front foot 11 and the rear portion of the band is adapted to extend under the rear foot 12, there being a slot 13 provided 50 in the bottom surface of the rear foot for receiving the band.

55 The front foot 11 has screwed therein a hardened plug 14 having an upper serrated surface 14' projecting above the upper surface of the foot for engaging the lower portion b of the strap to frictionally hold it as the other end of the strap is stretched by the feed wheel.

As best shown in Figs. 1, 3 and 7, the front foot 11 is connected on one side of the strap position with a vertical longitudinally extending flange 15 which forms part of the main frame 10. Another vertical longitudinally extending flange 16 is laterally spaced from the flange 15 and parallel therewith, and flanges 15 and 16 are connected at the front of the tool by a transverse web 17, the rear ends of the flanges being connected by a transverse web 18. Preferably, the main frame includes a substantially horizontal rib portion 19 which extends rearwardly from the top of web 18 and curves downwardly at its rear to join the rear foot 12. Preferably, the frame also includes a horizontal rib 20 extending along one side of the tool and connecting the bottom portion of flange 15 with the foot 12. Thus the ribs 19 and 20 define a hand hole in the frame between the feet 11 and 12, for carrying and supporting the tool in a balanced position in one hand.

The feed wheel indicated generally at 21 is mounted between the flanges 15 and 16 directly over the plug 14, so that the overlapping ends of the strap may be gripped between the feed wheel and the plug. The feed wheel is journaled on a feed wheel shaft 22 having its ends extending through slotted openings 23 in the flanges 15 and 16. The shaft 22 is normally positioned in the lower ends of the slots 23, as indicated in Fig. 2, and the slots extend upwardly and forwardly therefrom for a purpose to be described. Preferably, the outer ends of the shaft 22 are grooved and carry split retaining rings 24 which retain washers 25 engirdling the shaft and covering the slots 23.

The shaft 22 is swingably supported on the flanges 15 and 16 by a pair of links 26 which are pivoted at their upper ends on pins 27 secured in the flanges 15 and 16, the shaft 22 being journaled in the lower ends of the links 26. The angle of inclination of the slots 23 substantially coincides with arcs on a radius measured from the pivot pins 27 as the centers, and the shaft has enough clearance in the slots so that as the shaft 22 is swung in the links the shaft can move in the slots 23 from one end to the other, thereof the slots 23 acting as guides for the shaft.

As shown, the feed wheel 21 is provided with laterally spaced circular serrated portions 29 which are adapted to grip the upper overlapped portion *b'* of the strap as best shown in Fig. 7. Between the serrated portions 29 the feed wheel is provided with a recessed circular series of ratchet teeth 30 which are adapted to be engaged by a driving pawl 31 at the rear of the feed wheel and by a holding pawl 32 at the front thereof. The holding pawl is journaled on a pawl shaft 33 having its ends mounted in the flanges 15 and 16 with split retaining rings 34 on the projecting ends of the shaft. A coil spring 35 is looped over the upper end of the pawl and is coiled around the shaft 33 with its free ends abutting the web 17 so as to urge the end of the pawl into holding engagement with the ratchet teeth 30, as best shown in Fig. 4. Collars 36 on the shaft 33 at each side of the holding pawl 32 carry relatively heavy coil springs 37, the rear ends 38 of which press downwardly on the lower ends of the links 26 and normally urge the shaft 22 rearwardly downward against the lower ends of slots 23.

The oscillating handle 40 for rotating the feed wheel is provided at its front end with a yoke

comprising laterally spaced arms 41 which straddle the feed wheel and fit between the feed wheel and the links 26, the front ends of the arms being journaled on the feed wheel shaft, as best shown in Fig. 7. The handle 40 preferably has an inverted U-shape in cross section and has a knob 42 on its rear end.

The driving pawl 31 is pivoted on a pin 43 extending between and mounted in the arms 41 of the handle yoke, the lower end 44 of the pawl being adapted selectively to engage the ratchet teeth 30 of the feed wheel to drive the same in a clockwise direction, so that the serrations 29 grip the upper end portion of *b'* of the band and slide it over the lower portion *b* which is frictionally held stationary by the plug 14. A coil spring 45, looped over the end 44 of the pawl and wrapped around the pin 43, with its free ends abutting a pin 46 secured between the yoke arms 41, urges the end 44 of the pawl into driving engagement with one of the teeth 30 of the feed wheel.

Thus, if the handle 40 is raised to the dot-dash position shown in Fig. 4, the pawl ratchets over the teeth 30 of the feed wheel and engages a higher tooth, whereupon when the handle is oscillated downwardly the feed wheel is rotated clockwise to slide the end *b'* of the band forwardly and tighten the band around a package, after which the overlapped ends can be sealed by a suitable sealing tool.

In order to raise the feed wheel to allow insertion or removal of the overlapped ends of the band, the feed wheel shaft 22 is raised to the upper ends of the slots 23. This operation is accomplished in the present improved tool by squeezing the handle 40 with the same hand that holds the tool with the fingers inserted under the rib 19, in the manner shown in Fig. 5. To raise the feed wheel, the upper end of the driving pawl 31 is pushed with the thumb to release the lower end 44 of the pawl, in the manner shown in Fig. 5, the pawl end 44 being withdrawn into a notch 47 provided at the top of the web 18, best shown in Fig. 4.

The upper end of the pawl 31 is connected by means of a link 48 to the upper end of a stop arm 49 pivoted on a pin 50 secured in the handle 40, the lower end of the stop arm normally resting on the rib 19 of the frame and preventing further downward movement of the handle 40. When the pawl 31 is released by pushing forwardly on its upper end, the link 48 swings the lower end of the stop arm 49 rearwardly, as in Fig. 5, allowing the handle to swing downwardly until the yoke arms 41 rest on the shoulder 51 formed at the upper end of the web 18.

Now, if the handle 40 is squeezed toward the rib 19 of the frame, the handle will rock on the shoulder 51 as a fulcrum and raise the shaft 22 toward the upper ends of the slots 23, consequently raising the feed wheel 21 as shown in Fig. 5 to provide clearance between the feed wheel and the overlapped ends of the band to permit their insertion or removal. As shown in Figs. 4 and 5, a stop pin 52 may be provided at the rear of the pin 50 for abutting the stop arm 49 to limit its rearward swing.

Accordingly, when the operator of the tool desires to raise the feed wheel for inserting or removing the overlapped ends of the band, he merely pushes on the upper end of pawl 31 and then squeezes the handle without changing the tool in a balanced position, excepting to move position of his hand which normally carries the

his thumb slightly and then squeeze with the fingers. Thus the operator's other hand remains free for other operations such as positioning the overlapped ends of the band for ready insertion into the tool.

In operating the tool during the stretching operation, each time the handle is lowered, the stop arm 49 abuts the top of rib 19 and prevents the handle from rocking on the shoulder 51 and raising the feed wheel shaft 22. Thus the feed wheel drives the upper portion of the band forwardly without any slippage, because the downward motion of the handle tends to force the shaft 22 downwardly and increase the gripping action, and the shaft raises only when the pawl 31 is manipulated to swing the stop arm 49 rearwardly and allow the handle 46 to rock on the shoulder 51.

Moreover, the improved tool is always well balanced because there is no offset or laterally projecting adjusting handle as in many prior constructions. The tool is light in weight and inexpensive to manufacture and is easily carried and manipulated without resulting in fatigue of the operator.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiment of the improved construction illustrated and described herein is by way of example, and the scope of the present invention is not limited to the exact details of construction.

Having now described the invention, the construction, the operation and use of a preferred embodiment thereof, and the advantageous new and useful results obtained thereby; the new and useful constructions, and reasonable mechanical equivalents thereof obvious to those skilled in the art, are set forth in the appended claims.

We claim:

1. In a stretching tool, the combination of a frame, a feed wheel shaft, a feed wheel journaled on said shaft, means swingably mounting said shaft in said frame permitting raising and lowering said feed wheel, a handle lever journaled on said shaft, a ratchet pawl operatively connecting said handle lever to said feed wheel, a shoulder on said frame for abutting said handle lever, said shoulder providing a fulcrum about which the handle lever may rock to raise the feed wheel, and a stop arm pivoted on the handle lever operatively connected to said pawl and normally engaging the frame to prevent rocking the handle.

2. In a stretching tool, the combination of a frame, a feed wheel shaft, a feed wheel journaled on said shaft, links pivotally mounted on the frame and swingably mounting said shaft in said frame, said frame having guide slots receiving the ends of said shaft, a handle lever journaled on said shaft, a ratchet pawl operatively connecting said handle lever to said feed wheel, a shoulder on said frame for abutting said handle lever said shoulder providing a fulcrum about which the handle lever may rock to swing the feed wheel upwardly, and a stop arm pivoted on the handle lever operatively connected to said pawl and normally engaging the frame to prevent rocking the handle.

3. In a stretching tool, the combination of a

frame, a feed wheel shaft, a feed wheel journaled on said shaft, links pivotally mounted on the frame and swingably mounting said shaft in said frame, said frame having guide slots receiving the ends of said shaft, spring means urging said shaft to lowered position, a handle lever journaled on said shaft, a ratchet pawl operatively connecting said handle lever to said feed wheel, a shoulder on said frame for abutting said handle lever said shoulder providing a fulcrum about which the handle lever may rock to raise the feed wheel, and a stop arm pivoted on the handle lever operatively connected to said pawl and normally engaging the frame to prevent rocking the handle.

4. In a stretching tool having a frame, a shaft, a feed wheel journaled on the shaft, and a tensioning handle lever journaled on said shaft for actuating the feed wheel, links upon the frame swingably mounting said feed wheel shaft in said frame for raising and lowering movement, said frame having guide slots receiving the ends of the feed wheel shaft, and a shoulder on the frame for abutting an intermediate portion of the handle said shoulder providing a fulcrum about which the handle may rock to raise the feed wheel, and a stop movably mounted on the handle for normally engaging the frame to prevent the handle from contacting said shoulder.

5. In a stretching tool having a frame, a feed wheel, a shaft for the feed wheel journaled in the frame, a tensioning handle journaled on said shaft, and a ratchet pawl connecting said handle to said feed wheel, links pivotally mounted on the frame and swingably mounting said shaft on said frame, said frame having slots receiving and guiding said shaft, a rib extending longitudinally of the frame and forming a hand hole therein, a shoulder at the front end of said rib for abutting an intermediate portion of the handle in lowered position, and a stop arm pivoted on the handle operatively connected to said pawl and normally engaging said rib when the handle is lowered, whereby releasing said pawl will release said stop arm and allow squeezing the handle downwardly toward said rib to rock said handle on said shoulder and raise the feed wheel.

6. In a stretching tool having a frame, a feed wheel, a shaft for the feed wheel journaled in the frame, a tensioning handle journaled on said shaft, and a ratchet pawl connecting said handle to said feed wheel, links pivotally mounted on the frame and swingably mounting said shaft on said frame, said frame having slots receiving and guiding said shaft, a rib extending longitudinally of the frame and forming a hand hole therein, a shoulder at the front end of said rib for abutting an intermediate portion of the handle in lowered position, spring means urging said feed wheel to lowered position, and a stop arm pivoted on the handle operatively connected to said pawl and normally engaging said rib when the handle is lowered, whereby releasing said pawl will release said stop arm and allow squeezing the handle downwardly toward said rib to rock said handle on said shoulder and raise the feed wheel.

BERNARD T. McFERREN.
